Edward Richter, Freeport, Ill., assignor to Henney
Motor Company, Freeport, Ill., a corporation of Delaware

Application December 31, 1934, Serial No. 54,658

Term of patent 14 years

To all whom it may concern:

Be it known that I, Edward Richter, a citizen of the United States, residing at Freeport, in the county of Stephenson and State of Illinois, have invented a new, original, and ornamental Design for a Caster, of which the following is a specificcation, reference being had to the accompanying drawing, forming part thereof.

In the drawing:

Figure 1 is a perspective view of a caster showing my new design, and

Figs. 2 and 3 are a side view and plan view, respectively.

I claim:

The ornamental design for a caster substantially as shown.

EDWARD RICHTER.
